US0D1012416S

(12) **United States Design Patent** (10) **Patent No.:** **US D1,012,416 S**
(45) **Date of Patent:** **** Jan. 23, 2024**

(54) **PALLET**

- (71) Applicant: **THE HERSHEY COMPANY**,
Hershey, PA (US)
- (72) Inventor: **Steven A. Weis**, Hershey, PA (US)
- (73) Assignee: **The Hershey Company**, Hershey, PA (US)
- (**) Term: **15 Years**
- (21) Appl. No.: **29/810,809**
- (22) Filed: **Oct. 8, 2021**
- (51) LOC (14) Cl. **09-08**
- (52) U.S. Cl. **USPC D34/38**
- (58) **Field of Classification Search**

(57) **CLAIM**

The ornamental design for a pallet, as shown and described.

DESCRIPTION

FIG. 1 is a top perspective view of a pallet, showing my new design;

FIG. 2 is a top view thereof;

FIG. 3 is a first side view thereof;

FIG. 4 is a second side view thereof;

FIG. 5 is a first end view thereof;

FIG. 6 is a second end view thereof;

FIG. 7 is a bottom view thereof; and,

FIG. 8 is a bottom perspective view thereof.

The dot-dash broken lines define the bounds of the claimed design that form no part of the claimed design. The broken line pallets in the drawing depict environment which form no part of the claimed design. All other broken lines depict portions of the pallet that form no part of the claimed design.

1 Claim, 5 Drawing Sheets
